UNITED STATES PATENT OFFICE.

JOHN CLULEE, OF WALLINGFORD, CONNECTICUT, ASSIGNOR TO INTERNATIONAL SILVER COMPANY, OF MERIDEN, CONNECTICUT, A CORPORATION OF NEW JERSEY.

DESIGN FOR A HANDLE FOR SPOONS, FORKS, OR SIMILAR ARTICLES.

No. 38,611.

Specification for Design.

Patented June 11, 1907.

Application filed May 15, 1907. Serial No. 373,886. Term of patent 7 years.

To all whom it may concern:

Be it known that I, JOHN CLULEE, a citizen of the United States, residing at Wallingford, in the county of New Haven and State of Connecticut, have invented a new, original, and ornamental Design for a Handle for a Spoon, Fork, or Similar Article; and I do hereby declare the accompanying drawings to be a full, clear, and exact illustration of the same, and which said drawings consti-

tute part of this specification, and represent in a face view of a handle for a spoon, fork, or similar article embodying my design.

Claim.

The ornamental design for a handle for a spoon, fork or similar article, as shown.

JOHN CLULEE.

Witnesses:

JOHN A. MARTIN,
HENRY MARTIN.
